INTERMITTENT INDUCTIVE A. C. TRAIN CONTROL SYSTEM

Filed March 12, 1927

C. F. Estwick, INVENTOR
BY Neil F. Preston, ATTORNEY

UNITED STATES PATENT OFFICE.

CHARLES F. ESTWICK, OF ROCHESTER, NEW YORK, ASSIGNOR TO GENERAL RAILWAY SIGNAL COMPANY, OF ROCHESTER, NEW YORK.

INTERMITTENT INDUCTIVE A. C. TRAIN-CONTROL SYSTEM.

Application filed March 12, 1927. Serial No. 174,859.

This invention relates in general to railway train control systems, and has more particular reference to an automatic intermittent inductive alternating current type of system.

It is usual in systems of the character in question to control a brake applying or train movement restricting device in accordance with traffic conditions ahead, by means of co-acting trackway inductors and a car-carried receiver arranged to pass over the inductor in inductive relation thereto. In such systems it is quite essential that the operation of the inductors and receivers be certain and uniform.

With the above and other considerations in mind, it is proposed, in accordance with this invention, to provide an improved type of inductor and receiver. More specifically, the inductors comprise spaced parallel magnetic cores with coils thereon connected up through a tuned circuit to be controlled in accordance with traffic conditions ahead, while the receivers comprise two opposed spaced parallel cores with an obliquely arranged core therebetween, the cores being supplied with primary and secondary windings, properly placed, for accomplishing the desired results.

Further objects, purposes, and characteristic features of the invention will appear as the description progresses, reference being had to the accompanying drawings, showing solely by way of illustration, two physical embodiments of the invention, in connection with a simplified train control system. In the drawings:—

Fig. 1 is a schematic representation of apparatus in accordance with this invention; Fig. 2 is a schematic showing of a portion of the apparatus in a different operative position from that of Fig. 1; and

Fig. 3 shows a slightly modified arrangement of parts of the system.

Referring to the drawings, and more particularly to Fig. 1, a stretch of trackway is shown constituted by track rails 1, separated into signalling blocks by insulating joints 2. Each block has a usual track relay 3 at its entrance end and a track battery 4 at its exit end. Signals 5, of the semaphore type, have been shown at the entrance end to each block, but these could obviously be of any other desired type.

The trackway inductor of this invention is positioned adjacent the entrance end of each block and comprises two parallel spaced cores 6, preferably of laminated material, supplied with windings 7 connected in series with each other, with a condenser 8, and a contact finger 9 and front contact of the adjacent track relay, the constants of the circuit being such as to give the maximum clearing effect, that is, the maximum holding up effect on a car-carried main relay, when inductively influencing a car-carried receiver.

The various operating circuits and devices for controlling the wayside signals, can be of any usual or desired type, and are well understood by those skilled in this particular art.

The apparatus carried by the car, represented diagrammatically by wheels and axles 10, includes the receiver of this invention, comprising spaced parallel cores 11, with a pivoted, obliquely positioned, core 12 therebetween, all of which are preferably made of laminated material to cut down losses. On opposite ends of the core 12 are primary windings P^1 and P^2 connected in series with each other, with a tuning condenser 13, and a source of alternating current 14. The current supplied by the source 14 is preferably of a frequency higher than the usual commercial frequencies, and is of the order of 360 cycles per second, for example.

On opposite ends of the parallel spaced cores 11, are secondary windings S^1 and S^2 , connected in series with each other, with a tuning condenser 15, and a main control relay MR.

As is usual in systems of this character, a means, EPV, is provided for controlling the car brakes or imposing any desired speed restricting influences on the car, and in the case represented, is an electro-magnetic device which is normally energized through a circuit including a battery 16 or its equivalent, and contact finger 17 and front contact of relay MR. The brake device EPV, when de-energized, operates to exert a train movement restricting influence of the desired character.

The receiver is positioned on the car so as to pass directly over the trackway inductors, in the manner indicated in Fig. 2, at the entrance to each block, there being a short vertical air gap between the inductor and receiver

through which the receiver is inductively influenced under certain conditions, to be described below.

As an alternative arrangement, the inductor core 6 can be placed to parallel the track rails 1, with the receiver correspondingly changed in position, as shown in Fig. 3, with which arrangement the effect of the inductor on the receiver, is felt sooner before, and continued longer after, passage of the receiver directly over the inductor, than with the first arrangement (Figs. 1 and 2).

Each trackway inductor, as shown, is controlled by a track relay to place the windings 7 in either open or closed circuit condition. When the windings 7 are in a closed circuit, their choking effect is so great, that the cores 6 offer substantially no better path for flow of magnetic flux than does a corresponding air path, whereas, when these coils are open circuited, so that no current can flow therethrough, the cores 6 offer a good path for flow of magnetic flux. Thus, when track relay 3 is de-energized, the inductor is in active condition, while when energized, it is inactive. While the arrangement shown in the drawing permits of only two controls for the inductor, namely, clear and danger, it is obvious that a usual line relay, having a front contact included in the circuit of the windings 7, and controlled in accordance with traffic conditions in the second block in advance of the inductor in question, could be used, for the inductor to be controlled to be active under both caution and danger conditions, and inactive under clear conditions. An example of this type of control is shown in the patent to W. K. Howe, 1,604,098 of October 19, 1926, to which attention is directed.

Under normal conditions, the current supplied to the primary windings P^1 and P^2 , produces oppositely directed, opposing, fluxes in the core 11, in the manner indicated by the arrows in Fig. 1, and these fluxes follow the magnetic circuit having the least reluctance, which results in the flux produced by winding P^1 passing through secondary winding S^1 , in the direction indicated by the arrow (Fig. 1) while that produced by primary winding P^2 , passes through secondary coil winding S^2 in the direction indicated by the arrow (Fig. 1). The windings S^1 and S^2 are so connected as to have their induced voltages cumulative, whereby to send induced current through the winding of the main relay MR and thus maintain the brake device EPV in energized condition.

When an inductor is in inactive condition, that is, closed circuited, such as occurs under clear conditions, and is passed over by a receiver, the flux distribution in the various receiver cores 11 and 12 is not materially changed, since the choking effect of the windings 7 effectively prevents passage of flux

therethrough, and as a result the relay MR remains energized and no restricting influence is incurred.

Assuming, however, that the train in question is passing into a caution or danger block, under which conditions the windings 7 of the inductor at the entrance to such block are open circuited so that the inductor is active, a re-distribution of magnetic flux in the receiver takes place. The inductor cores 6 span across the ends of the receiver cores 12 (Fig. 2) and provide a second and alternative, magnetic path for the flux produced by each primary winding P^1 and P^2 , in a direction as indicated by arrows 18 in Fig. 2. The air gap between the inductor and receiver, and the proportions of the various parts, and the adjustment effected by rocking core 12 on its pivot, are such as to make the reluctances of the two alternative magnetic paths for flow of the flux produced by each primary winding, substantially equal. It will be noted that the existence of two paths in question, for each primary flux, tends to cause flux to pass through the secondary windings in opposite directions so as to counter-act each other as indicated by the arrows in Fig. 2. If the reluctances of the alternative paths in question be exactly equal, and the fluxes in phase no flux will pass through the secondary windings whereas, if they are somewhat unequal, or somewhat out of phase, a small resultant amount of flux will pass through the secondary windings in one direction or the other. In any event, however, on the passage of a receiver over an active inductor, the voltages induced in the secondary windings S^1 and S^2 will be reduced to zero or will be so substantially reduced, as to cause de-energization of main relay MR, with a resulting de-energization of EPV and the imposition of a train movement restricting influence.

In the drawing, no usual acknowledging and reset devices have been shown in connection with the brake applying apparatus, but such devices obviously could be utilized if desired, in any usual or conventional way, such as is illustrated, and described, for example, in the Howe Patent 1,604,098, referred to above. With such devices used in connection with the system shown, by proper operation of the acknowledging device, the train movement restricting influences can be prevented even though relay MR be de-energized, while if such restricting influence be incurred, operation of the reset device will restore the various parts to normal position.

It is important to note, in connection with the receiver described and illustrated, that the two primary windings P^1 and P^2 cause fluxes to flow in opposite and opposed directions, and furthermore, that the secondary windings have their induced voltages changed by a tendency for flux to reverse its direction

of flow therethrough, and that there has not been provided, in said receiver, as is usual practice, a separate bucking winding which has, at times, a voltage induced therein which is opposed to that in the secondary windings, and connected in series therewith. In the use of a bucking winding, should such winding be shunted out by a short circuit or the like, the system would operate to give a false clear 10 indication whereas, any shunting out of the secondary windings in the present instance would cause only a false danger indication, and so that all errors are on the side of safety.

The above rather specific description of 15 one form of the invention, is given solely by way of example, and is not intended, in any manner whatsoever, in a limiting sense. Obviously, the invention can assume many different physical forms, and is susceptible of 20 numerous modifications, and it is intended to include, in this application, all such forms and modifications as come within the scope of the appended claims.

Having described my invention, I now 25 claim:—

1. In a train control system, a car-carried receiver, comprising, two parallel, spaced cores, a secondary winding on each core, a core obliquely positioned between the parallel 30 cores, primary windings placed on the oblique core to be nonsymmetrical relative to said parallel cores, means for energizing the primary windings with alternating current, and a break applying device controlled by the secondary windings.

2. In a train control system, a car-carried receiver, comprising, two parallel, spaced cores, a secondary winding on each core, an obliquely positioned core between the parallel 40 cores, primary windings on the oblique core nonsymmetrical relative to said parallel cores, means for energizing the primary windings with alternating current, a brake applying device controlled by the secondary windings, 45 and a cooperating trackway inductor, including spaced parallel inductor cores positioned at right angles to the parallel cores of the receiver.

3. In a train control system, a car-carried 50 receiver, comprising, two parallel, spaced cores, a secondary winding on each core, a core nonsymmetrically positioned between the parallel cores, primary windings on the last mentioned core positioned nonsymmetrically 55 relative to said parallel cores, means for energizing the primary windings with alternating current, a brake applying device controlled by the secondary windings, and a cooperating trackway inductor, including 60 spaced parallel inductor cores positioned at right angles to the receiver parallel cores, and in a plane substantially parallel with that of the receiver cores.

4. In a train control system, a car-carried 65 receiver, comprising, two parallel, spaced

cores, a secondary winding on each core at non-opposed ends thereof, a core obliquely positioned between the parallel cores, primary windings on the oblique core at the respective ends thereof, means for energizing 70 the primary windings with alternating current, and a brake applying device controlled by the secondary windings.

5. In a train control system, a car-carried receiver, comprising, two parallel, spaced 75 cores, a secondary winding on each core at non-opposed ends thereof, a core obliquely positioned between, and inductively related to, the parallel cores, primary windings on the oblique core, means for energizing the primary windings in series with alternating current, and a brake applying device controlled by induced current flowing in the secondary windings.

6. In a train control system, a car-carried receiver, comprising, two parallel, spaced 80 cores, a secondary winding on each core at non-opposed ends thereof, a core obliquely positioned between the parallel cores, primary windings on the oblique core at the 85 respective ends thereof, and inductively related to the secondary windings, means for energizing the primary windings in series with alternating current, and a train restricting device controlled by induced current flowing in the secondary windings.

7. In a train control system, a car-carried receiver, comprising, two parallel, spaced 90 cores, a winding on each core at non-opposed ends thereof, a core obliquely positioned between the parallel cores, windings on the oblique core, at the respective ends thereof, and inductively related to the first said windings, means for energizing one set of windings with alternating current, a brake applying device controlled by the other set of windings, the energized windings being arranged to produce fluxes flowing toward each other, and the other secondary windings being arranged to cause fluxes to flow in opposite directions.

8. In a train control system, a car-carried receiver, comprising, two parallel, spaced 100 cores, a secondary winding on each core at non-opposed ends, thereof, a core obliquely 105 positioned between and in inductive relation to, the parallel cores, primary windings on the oblique core at the respective ends thereof, means for energizing the primary windings in series with alternating current, a train restricting device controlled by induced current flowing in the secondary windings, the primary windings being arranged to produce fluxes flowing toward each other, and the secondary windings being arranged to cause 110 fluxes to flow therethrough in opposite directions.

9. In a train control system, a car-carried receiver, comprising, two parallel, spaced 115 cores, a secondary winding on each core, an 120

adjustable, obliquely positioned core between the parallel cores, primary windings on the oblique core, means for energizing the primary windings with alternating current, and 5 a train restricting device controlled by the secondary windings.

10. In a train control system, a car-carried receiver, comprising, two parallel, spaced cores, a secondary winding on each core, a 10 rotatably adjustable, obliquely positioned, core between the parallel cores, primary windings on the rotatably adjustable core, means for energizing the primary windings with alternating current, and a train restricting 15 device controlled by the secondary windings.

11. In a train control system, a car-carried receiver, comprising, two parallel, spaced cores, a secondary winding on each core, an obliquely positioned core between the parallel 20 cores, primary windings on the oblique core positioned nonsymmetrically relative to said parallel cores, means for energizing the primary windings with alternating current, a

brake applying device controlled by the secondary windings, and a cooperating trackway 25 inductor, including spaced parallel inductor cores positioned at right angles to said parallel cores, for respectively spanning across the ends of the said parallel cores.

12. In a train control system, a car-carried receiver, comprising, two parallel, spaced cores, a secondary winding on each core, an obliquely positioned core between the parallel cores, primary windings on the oblique core positioned nonsymmetrically relative to said parallel cores, means for energizing the primary windings with alternating current, a 30 brake applying device controlled by the secondary windings, and a cooperating trackway inductor, including spaced parallel inductor cores positioned at right angles to said parallel cores, for respectively and simultaneously spanning across the ends of the said parallel cores. 35

In testimony whereof I affix my signature.
CHARLES F. ESTWICK.
